HEATER CONSTRUCTION

Filed Jan. 25, 1939

FIG. I.

FIG. II.

INVENTOR:
George Faulds,
Paul Paul
ATTORNEYS.

UNITED STATES PATENT OFFICE

2,276,474

HEATER CONSTRUCTION

George Faulds, Philadelphia, Pa.

Application January 25, 1939, Serial No. 252,733

1 Claim. (Cl. 122—218)

This invention relates to heater construction and more particularly to a crown component or section for domestic and similar heaters, the primary object being to provide a novel type of crown component for the suspension therefrom of a heat retainer and diffuser unit of the type disclosed in my prior application for patent Serial No. 249,675, filed January 7, 1939, and which later matured as U. S. A. Patent No. 2,200,985, dated May 14, 1940.

Another object is the provision of a crown component or section which is adapted preferably for new heaters, but which may be substituted for existing heater top sections, whether round or of the sectional type.

The invention further comprehends certain features of construction, combinations and arrangements of parts that will hereinafter more fully appear, and be particularly pointed out in the concluding claim.

Reference will now be had to the accompanying drawing, in which there are exhibited practical embodiments of the invention.

In the drawing:

Fig. I is a broken vertical section of a standard type domestic round heater embodying one form of the present improvements.

Fig. II is a broken plan section, taken approximately on the plane designated II—II in Fig. I.

Fig. III is a fragmentary vertical section of a modified form of this invention.

Referring in detail to the drawing, and firstly to Figs. I and II more particularly, the improved heater component or section 1, therein shown, embodies a hollow annular portion 2, with an intermediate and communicating chambered-crown 3, having a central draft orifice 4 therethrough. The section 1 is preferably of cast metal, and it is provided, at predetermined points, with integrally-formed axially cored out hubs or studs 5 for passage of the screw-threaded upper portions 6 of suspension members or rods 7, said rods being rigidly retained in position by upper and lower lock washers 8 and nuts 9. Or, as shown in Fig. III, the central draft orifice 4 may include upper and lower spiders

10, 11, respectively, formed integral with the component 1, and each having an axial opening 12 for passage of a single suspension rod 7 with applied clamp nuts 13. Each of the suspension rods 7 has the lower or other end screw-threaded at 14, and is fitted with a lock washer 15 and nut 16, for a purpose later explained.

Adapted for support by the rods 7 is the substantial heat-retainer and diffuser unit 20, preferably of the type set forth in the hereinbefore referred to patent, said unit having borings 21 therethrough for passage of the rods 7, and it is sustained at the required elevation, relative to the crown section 1, by the lock washers 15 and nuts 16, in an obvious manner. The unit 20 also includes surrounding baffles 22, and a spreader 23 to prevent unconsumed fuel particles entering the central draft orifice 4.

In Fig. III, it is to be noted the upper screw-threaded portion 6 of the suspension rod 7 is provided with an additional nut 24 functional to initially support the spreader 23 when assembling the unit 20 below the heater section 1, whereby the necessity of otherwise holding said spreader 23 to prevent unconsumed fuel particles entering the central draft orifice 4.

From the foregoing description, it is thought the merits and advantages of this invention will be clearly understood, also that minor changes are comprehended as coming within the scope of the following claims.

Having thus described my invention, I claim:

A component section for domestic heaters comprising a hollow annular portion, a transverse communicating planar section intermediate the upper and lower ends thereof, a draft orifice through said section, and apertured means integral with the walls of the planar section; in combination with a heavy heat retainer-and-diffuser unit having borings therethrough for alignment with the heater component planar section apertured means, and suspension means engageable through the said unit borings and component section apertured means for central support of the former pendently by the latter.

GEORGE FAULDS.
